FIG. 1.

FIG. 2.

Paul M. Hunt
P.C. Lannon
WITNESS:

C. E. McManaman
INVENTOR
BY *Victor J. Evans*

ATTORNEY

UNITED STATES PATENT OFFICE.

CHARLES E. McMANAMAN, OF SWAYZEE, INDIANA.

LIGHTER.

Application filed August 11, 1923. Serial No. 656,966.

This invention relates to improvements in ignition devices and has for an object the provision of a device which may be applied to an oil burner to afford convenient means 5 for lighting the wick.

More specifically, the invention aims to provide an electric lighting device which may be attached to a burner (such as an oil stove burner) whereby the wick may be 10 lighted by closing a circuit.

With the above and other objects in view, the invention further includes the following novel features and details of construction, to be hereinafter more fully described, illustrated in the accompanying drawings and 15 pointed out in the appended claim.

In the drawings:—

Figure 1 is a top plan view of the burner of an oil stove equipped with the invention.

Figure 2 is an enlarged sectional view 20 taken on the line 2—2 of Figure 1, a fragmentary portion of the bottom of the stove being also shown.

Referring to the drawings in detail 25 wherein like characters of reference denote corresponding parts, the reference character 10 indicates a portion of the bottom or base of an ordinary oil stove having a burner suitably supported and spaced above the same, the said burner including an inner cylinder 11 and an outer cylinder 12. The cylinders 11 and 12 are as usual, spaced apart to accommodate a wick 13.

The outer cylinder 12 is of less height 35 than the inner cylinder 11 and mounted upon this outer cylinder is a ring or annulus 13' whose upper edge is spaced slightly above the upper edge of the inner cylinder 11. This ring or annulus is reduced to provide 40 a shoulder 14 which rests upon the outer edge of the outer cylinder 12 so that the ring or annulus 13' will be removably held in place.

This ring or annulus is constructed of a 45 suitable insulating material, such as porce-

lain or the like and has mounted thereon an ignition element or point 15. This element 15 is connected by means of a conductor 16 with a push button switch 17 and the latter has connected thereto a conductor 18. A 50 conductor 19 is connected to the inner cylinder 11 and connecting the conductors 18 and 19 is a battery 20 and a spark coil 21.

When a circuit is closed by the operation of the push button switch 17, through the 55 battery and spark coil, a spark will jump from the ignition element 15 to the upper edge of the inner cylinder 11 and the wick will thus be ignited.

The invention is susceptible of various 60 changes in its form, proportions and minor details of construction and the right is herein reserved to make such changes as properly fall within the scope of the appended claim.

Having described the invention what is 65 claimed is:—

An igniter of the character described comprising a base, a pair of cylindrical members of different diameters providing inner and 70 outer sections respectively, the inner section extending above the upper periphery of its companion section, a wick interposed between the sections and having an appreciable portion exposed, a dielectric annulus 75 having its lower portion reduced in thickness mounted upon and encircling the outer section and having its enlarged portion resting upon the upper periphery thereof, a sparking point carried by said annulus and in 80 juxtaposition with the upper periphery of the inner section, electric conducting means connected with a suitable source of energy which is in turn connected with the inner section whereby the circuit when closed will 85 cause a spark to jump from the sparking point to the upper periphery of the inner section in order that the wick may be ignited.

In testimony whereof I affix my signature.

CHARLES E. McMANAMAN.
